APPARATUS FOR EMBOSsing FABRICS

Application filed June 17, 1930, Serial No. 461,723; and in Great Britain September 25, 1929.

This invention relates to apparatus for ribbing flexible material, and it has for its object to provide simple and efficient apparatus whereby fabrics or other flexible material may be ribbed to produce a decorative effect.

According to this invention the ribbing is produced by means of dies acting upon the material in a manner such that the part to be permanently raised is pressed out of the plane 10 of the material, and when in this condition is subjected to laterally applied pressure, the parts, if desired, being heated to ensure the setting of the material.

According to this invention the ribbing is effected by means of a die comprising two 15 jaws or members, one or both of which may have a reciprocal motion, said members being provided upon the upper surfaces with raised or sharpened edges, which press into the material so that when the jaws are closed they 20 will act to compress the material between them. In order to secure the effective operation of the jaws, there is provided a member 25 designed to engage the outer surface of the material, such member being composed of or having a surface formed of some yielding material, such for example, as felt.

In order that the invention may be the better understood, the accompanying drawings are appended, in which:

Fig. 1 is a front view of a machine embodying the present invention.

Fig. 2 is a transverse section on line A—A Figure 1.

Fig. 3 is an end view.

Figs. 4 and 5 are sectional views to a larger scale, showing certain details.

Figs. 6 and 7 are perspective views showing certain further details.

Referring to the accompanying drawings, 40 1 indicates generally the frame of the machine which comprises end members 2, 2 held together in spaced relationship by means of tie bars 3.

Disposed between the members 2 and supported thereon at its ends is an inclined plate 4 extending transversely of the machine and having at its lower end a ridge 5, between which and the upper portion of the said plate 50 is disposed a channel or groove 6 in which

is disposed a heating element 7 above which is situated a die 9 comprised of jaws 9^a, 9^b, extending from side to side of the said plate and normally maintained in spaced relationship by means of springs such as 10 disposed at suitable intervals throughout the length of the die and located within recesses 11 formed within the inner faces of the jaws, the ridge 5 acting to support the lower die 9^b.

The jaws 9^a, 9^b are provided at their inner upper edges with projections 12, 12^a, having substantially sharp edges, the arrangement being such that when a felt pad 13 carried upon a bar 14 is lowered onto the material, which is fed, by means which will be herein-after more fully described, over the projections 12, 12^a as shown more clearly in Fig. 4, to press the material onto the said projections, and the jaw 9^a is moved, by means which will also be later described, toward the jaw 9^b, the material is caused to bulge between the said jaws as shown in Figure 5, and thus enables them to compress the same to form the rib.

15 indicates the flywheel of the machine which may be connected by means of a belt to a driving motor, not shown, the motion thus received being communicated through a transmission gear disposed within the gear box 16 to a cam shaft 17 extending transversely of the machine and journalled at its ends in bearings formed within the members 2.

Mounted at points near each end of the shaft 17 is a cam 18 which engages with a 35 roller 19 mounted upon the lower end of a body 20 designed to be periodically moved by the said cam against the action of a spring 21, and supported at its lower end upon the shaft 17 which passes through a slot 22 with- 40 in the said body.

Disposed upon the plate 4 at a point slightly above the jaw 9, and extending from side to side of the said plate, is a body 23 which is slidably mounted and connected at its ends 45 to the bodies 20 at each side of the machine, each of the said bodies being provided with a slot 20^a through which the ends of the body 23 pass, suitable adjusting bolts 24 and 24^a being provided respectively within the bodies 50 55 60 65 70 75 80 85 90 95 100

20 and 23 for effecting the adjustment of the body 23 longitudinally of the slots 20^a, this last mentioned body being operatively connected by means of adjusting screws 25 to the upper jaw 9^a to cause the same to be periodically moved toward the jaw 9^b.

In order to prevent the lateral displacement of the body 23, end plates 26 are provided thereon, which are of somewhat greater width than the width of the slots 20^a.

27 indicates a shaft extending transversely of the machine and journaled at its ends in bearings formed in the frame members 2, and mounted upon each end of which shafts are the lower ends of inclined arms 28, having forked upper extremities, which serve to support the ends of a bar 29 extending transversely of the machine and connected by means of distance pieces to the bar 14, which, as previously stated, carries the felt pad 13.

The arms 28 are rigidly connected together by means of the tie-bar 30.

Mounted upon the shaft 27 at points near each end thereof, are downwardly extending arms 31 each provided at their lower ends with a roller 23 with which engages a cam 33 disposed upon the shaft 17, the arrangement being such that the cams 33 act through the arms 31 to reciprocate the arms 28 in suitably timed relationship to the reciprocation of the jaw 9^a toward and away from the jaw 9^b.

For the purpose of causing the pad 13 to be applied with the requisite pressure to the fabric, springs 34 are provided between the ends of the tie-bar 30 and levers 35 mounted upon the inner faces of the members 2 in the manner shown in Figure 2, the said levers at their forward ends extending somewhat beyond the forward edges of the said members upon which are mounted notched plates 36 with the notches of which the said levers are designed to engage, and whereby the tension of the said springs may be adjusted.

Extending transversely of the machine and slidably mounted by means of end plates 37 upon the upper portion of the plate 4 is a plate 38 provided at points near its ends with brackets 39 arranged perpendicularly thereto.

Carried at each of its ends by the lower portions of the brackets 39 is a transversely extending rod 40 of square cross-sectional outline, upon which is mounted the upper end of a vertically inclined plate 41 arranged parallel with the plate 4 and extending over the body 23 to a point near the jaw 9^a.

Carried between the upper ends of the brackets 39 and pivotally mounted therebetween is a rod 42 of similar cross-sectional outline to the rod 40 and disposed in parallel alignment therewith, and to which rod is secured the upper end of a plate 43 which is inclined with respect to the plate 41 and is

of such size that its lower end normally contacts with the lower end of the plate 41.

Mounted at their lower ends upon the extremities of the bar 42 and upon the forward face thereof, are vertically disposed bodies 44 having their upper ends bent over at a right angle to the main body portions thereof and provided thereat with screws 45 adjustable by means of butterfly nuts 46 and connected at their lower ends to the upper ends of springs 47 which in turn are connected at their lower ends to hooks or pins such as 48 carried by the bar 40.

The springs 47 are in a state of tension to thus maintain the required pressure of contact between the meeting edges of the plates 43 and 41, so that when the plate 38 is reciprocated, by means now to be described, in suitably timed relationship with the operation of the die, the material which passes between the plates 41 and 43, is fed from the roll indicated by α , carried upon the shaft 47, supported from brackets 48 upon the members 2, over the rollers 49 carried by brackets 50, also mounted upon the members 2, and into the machine.

The reciprocation of the plate 38 is effected by means of cams 51, 51 disposed at points near the end of the shaft 17 and between the cams 18 and 33.

The cams 51, 51 each engage with a roller 52 carried upon the lower end of an arm 53, each of which arms is pivotally connected at its upper end to its respective members 2, the said arms being of arcuate shape and provided throughout the major portion of their length with arcuate slots 54 through which pass adjustable bolts 55 which may be clamped in any position within the length of the said slots by means of butterfly nuts 56, and upon which bolts are pivoted the forward ends of links 57.

The links 57 are at their rear ends each provided with a stud such as 58 (Figure 2) which engages with the upper end of a slot 59 formed within the lower end of a vertically inclined strip 60 fixed at its upper end to its respective bracket 39 between which and the said stud is connected a spring 61, the arrangement being such that an elastic connection exists between the links 57 and the strips 60 during the forward movement of the plates 41 and 43, but during the return movement thereof the connection is positive owing to the fact that the stud 58 is in engagement with the upper end of the slot 59.

The purpose of this last mentioned arrangement is for permitting the plate 38 to be moved into its rear-most position independently of the operation of the machine should this for any reason be desired by grasping a handle 62 provided at the upper end of a lever 63 pivoted at its lower end to the frame of the machine and so disposed that it may be moved into engagement with

a pin 64 projecting from one of the brackets 39 as shown in Fig. 3.

65 indicates a handle disposed at the upper end of a rod 66 secured at its lower end 5 to the bar 42, the purpose of this being to permit the plate 43 to be moved out of contact with the plate 41 should this at any time be desired.

The cams 51 are so timed that the plates 10 43 and 41 which grip and feed the material between their forward edges, move forward during the period when the jaws 9^a, 9^b, of the die are apart and move rearwardly along the material during the periods when the 15 said jaws have firmly closed upon the material.

If desired a suitable tray or plate held by brackets such as 67 may be provided to receive the ribbed material as it leaves the machine.

In order to avoid any tendency of the plate 43 to buckle and cause the uneven feeding of the material it has been found advantageous to slot the said plate in the manner shown in 20 Figure 6.

The plate 4, a section of which is shown in Figure 7, is slotted in a similar manner to prevent its buckling owing to the action of the heat from the heater at its lower end.

30 Whilst we have described the preferred embodiment of the invention and have given a specific embodiment thereof, it is to be understood that the invention is not to be limited to such preferred embodiment, but 35 may be otherwise embodied within the scope of the following claims.

Claims:

1. Apparatus for ribbing flexible material comprising a member, a second member, 40 springs for holding said members normally apart, projections on said members, means for operating one of said members against the action of said springs, and means for causing the material to be alternately engaged and compressed by said members and for releasing same therefrom.

2. Apparatus for ribbing flexible material comprising a member, a second member, 50 springs for holding said members normally apart, projections on said members, means for operating one of said members against the action of said springs, and means for causing the material to be alternately engaged and compressed by said members and 55 for releasing same therefrom, and means for intermittently feeding the material at such times as it is not being acted upon by the said ribbing members.

3. Means for ribbing flexible material comprising a fixed body, a member supported 60 by said fixed body, a projection on said member, a movable body, a member carried by said movable body, means for reciprocating said movable body, means for intermittently feeding the material, and means for

causing the material to be engaged by the said projections and pressed between them.

4. Apparatus for ribbing flexible material comprising a member, a second member, 70 projections on said members, means for causing the material to be engaged by said projections, means for producing relative movement of the members to alternately compress the material between them and to free said material, and means for heating the ribbing 75 members.

5. Apparatus for ribbing flexible material comprising a fixed body, a member carried by said fixed body, a projection on said member, a movable body, a member carried by 80 said movable body, a projection on said second member, springs interposed between said members, means for heating said members carried by said fixed body, means for reciprocating said movable body, means for intermittently moving the material over said projections, a vertically reciprocating member carrying a pad designed to engage and press the material on to the projections.

6. Apparatus for ribbing flexible material 90 comprising a member, a second member, springs normally holding said members apart, projections on said members, means for causing said material to be engaged by said projections and means for producing relative movement of the members to alternately compress the material between them and to free said material.

7. Apparatus for ribbing flexible material 95 comprising a member, a second member, springs for holding said members normally apart, projections on said members, means for causing the material to be alternately engaged and compressed by said members and for releasing same therefrom, means for intermittently feeding the material at such times as it is not being acted upon by the said members, and means for heating the said members.

8. Apparatus for ribbing flexible material 100 comprising a member, a second member, springs for holding said members normally apart, projections on said members, means for operating one of said members against the action of said springs, means for intermittently feeding the material, a vertically reciprocating body disposed above the material, 105 a pad on said body designed to engage the material, and means operating said pad carrying body to cause same to engage the material and press same upon said projections.

9. Apparatus for ribbing flexible material comprising a fixed body, a member carried by 110 said fixed body, a projection on said member, a movable member designed to cooperate with said first member to press the material, a projection upon said second member, means for heating said members carried by said fixed body, a shaft, means operably connecting said movable member with said shaft to recipro-

cate said member, arms, a pad supported from said arms and disposed above the members, a second shaft carrying said arms, other arms upon said shaft, rollers on said arms, cams upon said first shaft engaging said rollers of said second arms, springs operating to draw said pad towards the ribbing members, means for feeding the material operated by said first shaft.

- 10 10. Apparatus for ribbing flexible material comprising a fixed body, a member carried by said fixed body, a projection on said member, a movable member designed to cooperate with said first member to press the material, a projection upon said second member, means for heating said members carried by said fixed body, a shaft, means operably connecting said movable body with said shaft to reciprocate said body, arms, a pad supported from said arms and disposed above the members, a second shaft carrying said arms, other arms upon said shaft, rollers on said arms, cams upon said first shaft engaging said rollers of said second arms, springs operating to draw said pad towards the ribbing members, a slide movable upon the fixed body, a plate carried by said slide, a second plate inclined with respect to said first plate, a spring acting upon said first plate to cause the inner edge thereof to engage the inner edge of the second plate, and grip the material passing between them, brackets, pivotally mounted arms upon said brackets, rollers upon said arms engaging cams upon the first shaft, links connecting said pivotally mounted arms with the slide and a spring opposing the movement of the said slide in one direction.

In testimony whereof we have hereunto set our hands.
